CLEANING ATTACHMENT FOR INTEGRAL
LINE-CASTING TYPE MACHINES

Charles A. Spickler, Yardley, Pa.

Application March 23, 1935, Serial No. 12,677

11 Claims. (Cl. 199—62)

My invention relates to cleaning attachment for integral casting type machines and particularly to mechanism for cleaning the knives by which the type slugs are trimmed to a predetermined thickness when ejected from the mould disk.

The invention relates more particularly to "Linotype" and "Intertype" machines. The final action of these machines is to trim the cast line (type slug) to a predetermined thickness by forcing it between perpendicular, parallel knives located in the first elevator and then depositing it into a line reservoir. This final operation leaves the trimming of excess metal adhering to the useful edges of the knives, the removal of which is the concern of this invention.

Because the trimming knives are "canted" one-eighth of an inch ($1^{\circ} 30'$) in five to lend a slicing motion and to ease the burden of ejection, the "canting" causes a mechanical difficulty, so that the perpendicular swipe of the "flag" can be only partially efficient.

Therefore, when the knives are improperly cleaned of slivers or ridges of excess type metal, during the next line ejection any slivers or ridges that happen on the useful edges of the knives are ejected with and adhere forceably to the type face of the slug and in print appear as tiny blots or blur the surrounding letters, which is an event of common occurrence, and is known to the trade as a "dirty face".

Examples of dirty face are common, even after the type has supplementary hand cleaning by the bankman, the corrector, the proofreader, the stone hand and by the revising proofreader. Slivers sometimes appear in printing plates prepared for long press runs of books.

While wipers are usually provided for removing such fragments from the trimming knives the wipers frequently operate improperly or bind so that chips still remain on the edges of the knife blades. Furthermore it has been the practice heretofore to actuate the wipers by the first elevator and in the event a slug sticks to the ejector or remains between the knife blades, as in the case of a "hot slug", the wiper cannot move up and down over the knife edges and the wiper fails to operate without giving any indication of the trouble to the operator.

In accordance with my invention these difficulties and disadvantages of constructions of the prior art are overcome and a simple, inexpensive wiper provided which functions to remove chips and fragments from the trimming knives very effectively. Moreover in a preferred form of my invention hereinafter described the wiper

is actuated by a manually controlled element of the mechanism such as the assembly elevator so that in the event the mechanism functions improperly due to a "hot slug" or for any other reason, the operator is immediately advised of the condition and can remedy the same so as to avoid further operation of the mechanism in an improper manner.

One of the objects of my invention is to provide a novel and inexpensive wiper construction for removing type metal from the edges of the trimming knives of integral line casting type machines.

Another object of my invention is to provide manually operated means serving to indicate improper operation of the mechanism.

A further object of my invention is to provide a wiper for the knife blades actuated by the assembly elevator.

These and other objects and features of my invention will appear from the following description thereof in which reference is made to the accompanying figures of the drawing which illustrate preferred embodiments thereof as applied to "Linotype" and "Intertype" machines.

In the drawings:

Fig. 1 is an end view of one form of wiper adapted for use in my invention.

Fig. 2 is a perspective of an attachment to be applied to existing "Linotype" machines and embodying my invention.

Fig. 3 is an elevation of the knife blades and a typical form of wiper embodying my invention as applied to a "Linotype" machine with parts broken away.

Figs. 4 and 4b are plan views of the knife wipers of Fig. 3.

Figs. 4a and 4c are end views of the knife wipers of Fig. 3.

Fig. 5 is a perspective of the movable knife block of a "Linotype" machine.

Fig. 6 is a perspective of the movable knife block of an "Intertype" machine.

Fig. 7 is an end view of the parts shown in Fig. 3.

Figs. 8 and 8a are plan and side views of a form of wiper moving strap adapted to be applied to the movable knife block of a "Linotype" machine.

Fig. 9 is an elevation of the knife blades and a typical form of wiper as applied to an "Intertype" machine with parts broken away.

Fig. 10 is a view of the parts shown in Fig. 9 taken at right angles thereto.

Figs. 11 and 11b are plan views of the wiper blades used in the "Intertype" machine.

Figs. 11a and 11c are end views of the wiper blades in the "Intertype" machine.

5 Fig. 12 is a perspective of the movable knife block of a "Linotype" machine with the wiper moving strap of Fig. 8 applied thereto.

10 Fig. 13 is an elevation of a typical form of attaching means for securing the wiping mechanism to the assembly elevators of existing machines, and

15 Fig. 14 is a similar view of the device as applied to a machine formed to receive the same, certain parts of the device being broken away.

20 In that form of my invention chosen for purposes of illustration in Figs. 1 to 5, 7, 8, 12 and 13 of the drawings I have illustrated a wiper in the form of an attachment to be applied to existing "Linotype" machines wherein there is a bracket 15 or other suitable means secured to the lower portion of the assembly elevator 39 by means of a set screw 38. An arm 24 extends from the bracket on the assembly elevator toward the mold disk and trimming knife and is 25 adjustably supported on a projection 35 of the bracket by means of the slot 36 and screw 37 on one end of the arm 24. Adjustment of the arm 24 by the set screw 38 or by the screw and slot 36 and 37 renders it possible to adjust position of 30 the arm and the tension of the wiper blades against the knives. Thus it is possible to urge the wiper toward the knife blades with a variable force depending upon the position of the arm and with resiliency thereof. In this way I insure 35 contact of the wiper with the knife edges throughout their length despite the fact that the knives are usually located in an inclined position.

40 A wiper 16 designed to cooperate with both of the knives 21 and 26 is carried by the arm 24. The wiper is secured to the arm by suitable screws or the like to permit removal or replacement thereof and is located closely adjacent to or in contact with the knife edges to remove fragments 45 of metal therefrom. As illustrated the wiper 16 may if desired have a lug 40 carried thereby and positioned to engage the fixed knife at a point spaced from its cutting edge so as to hold the wiper from direct contact with the knife edges as 50 the wiper moves up and down thereby prolonging their usefulness.

55 In the construction of Fig. 1 a single wiper serves to remove material from the edges of both knives. However, it may be desirable in some instances to employ a separate wiper for each knife edge. In the construction of Figs. 3 to 12 I have illustrated constructions wherein two separate wiper blades are provided. Although two 60 separate arms or supports for the separate wipers may be used I prefer, as shown, to support both wipers by the same arm 24. Since one of the blades is adjustable for the purpose of trimming the slugs to different thicknesses it is desirable when using two wiper blades to have the blade 65 associated with the movable knife adjustable with the knife. To this end I have shown the wiper 18 of Figs. 3 and 7 as secured to a block 20 formed with a recess engaging a projecting member on the movable knife. The projecting member may 70 conveniently be formed on a strap 22 secured to the knife by overhanging ends engaging the knife adjusting bolts 25 and knife retaining bolts 27, as shown in Figs. 7, 8 and 12. The construction shown in these figures of the drawings illustrates 75 the invention as applied to a "Linotype" machine

having a movable knife of the type shown in Fig. 5.

When this type of construction, that is one embodying two wipers, is used on an "Intertype" machine having a trimming knife of the type 5 shown in Fig. 6 the device may have the form illustrated in Figs. 9, 10 and 11, wherein the wiper 28 cooperates with the stationary knife 26 and the wiper 30 cooperates with the movable knife 34. The wiper support for the wiper 30 is formed 10 with a portion 31 extending into the longitudinal trough of the knife and with a portion 32 engaging the rear of the knife block 34 as shown in Fig. 10.

In the "Intertype" machine the movable blade 15 is adjusted by means of a knife setting device located between the knife and the assembly elevator. For this reason the arm 24 by which the wipers are carried in such constructions is offset as shown at the left hand side of Fig. 10 so as to 20 extend around the knife setting mechanism and between the same and the adjacent edge of the mold disk.

In each of the forms of the wiper construction shown in Figs. 3, 4, 9 and 11, the wiper extends lengthwise of the slot between the knife edges so as to bring the wiper into engagement with the entire length of the knife edges even when the length of movement of the wiper is less than the length of the mold slot or knives. 30

In the operation of the mechanism described the operator actuates the assembly elevator at the end of every line to raise the matrices into position to be moved over to the first elevator. The movement of the assembly elevator is effected 35 manually and involves vertical movement of the elevator in a line substantially parallel to the knife edges although spaced therefrom. The arm 24 and wipers are thus moved up and down at each operation of the assembly elevator and 40 with each transfer of a line of matrices to the first elevator for the formation of a slug.

The mold disk wheel of a line casting type machine when at rest, on its lock-up studs or while revolving is at no time closer than $\frac{1}{16}$ inch to the 45 useful edges of the trimming knives, and as the wiper plates are less than $\frac{1}{16}$ inch in thickness, the invention is at all times effective and meets an obstruction only when the ejector blade is performing its normal function of ejection or upon 50 the occurrence of a "hot slug".

If a "hot slug" is formed and the space between the mold slot and knives is obstructed with the assembly elevator either above or below the slug or the ejector blade, the assembly elevator will 55 not be permitted to operate in the proper manner and the operator will immediately be notified of the trouble. In this way manual operation of the wiper mechanism through the assembly elevator serves as a trouble indicator as well as a 60 simple and effective wiping device. An additional advantage of the device is that it allows the space and fastening points now taken by the old wiping systems to be used for other purposes if necessary, and eliminates a number of the moving 65 parts of the machine.

While I have indicated that the mechanism may be applied to existing machines as an attachment, as shown in Fig. 14 it may be embodied in new machines by the use of an integral projection or other means 35 for supporting the arm 24. However, I prefer to construct the arm 24 so as to be adjustable with respect to the assembly elevator by some such means as the slot 36 and screw 37 to permit variation in 75

the force with which the wiper blades engage the knives.

The forms of my invention herein shown and described are designed for use on "Linotype" and "Intertype" machines but it may be desirable to make numerous changes and modifications in the form and arrangement of the parts to adopt the same for use on other machines or to facilitate or reduce the cost of manufacturing or assembling operations. It should therefore be understood that those embodiments of my invention herein shown and described are intended to illustrate my invention and are not intended to limit the scope thereof.

15 I claim:

1. In combination with the slug-trimming knives of an integral line casting type machine having an assembly elevator, wiping means movable lengthwise of the knives and located in position to remove from the knives material adhering thereto, a bracket detachably secured to the assembly elevator and movable therewith and a support for said wiping means carried by said bracket.

2. In combination with the slug-trimming knives of an integral line casting type machine having an assembly elevator, wiping means movable lengthwise of the knives and located in position to remove from the knives material adhering thereto, a support for said wiping member movable with the assembly elevator and means for adjusting the position of said wiping means with respect to said assembly elevator.

3. In combination with the slug-trimming knives of integral line casting type machines, two wiping members one of which is positioned adjacent each of the knives to remove material therefrom and manually operable means for moving said wiping members.

40 4. In combination with the slug-trimming knives of an integral line casting type machine having an assembly elevator, two wiping members one of which is positioned adjacent each of the knives and movable with respect thereto to remove material from the knives and means actuated by the assembly elevator for moving said wiping members.

45 5. In combination with the slug-trimming knives of an integral line casting type machine having an assembly elevator, two wiping members one of which is positioned adjacent each

of the knives to remove material therefrom, a bracket secured to the assembly elevator and movable therewith and support means for both said wiping members carried by said bracket.

6. In combination with the slug-trimming knives of an integral line casting type machine having an assembly elevator, two wiping members one of which is positioned adjacent each of the knives to remove material therefrom, means for actuating said wiping members and means for retaining said members in substantially the same positions with respect to the knives with which they are associated when said knives are moved to various positions.

7. In combination with the movable slug-trimming knife of an integral line casting type machine, a wiping member positioned adjacent said knife to remove material from the knife edge and movable with said knife from one position to another.

8. In combination with the slug-trimming knives of integral line casting machines a wiping member movable lengthwise of the knives and located in position to remove from the knives material adhering thereto and means engaging one of said knives to hold said member in spaced relation to the knife edges.

9. In combination with the slug-trimming knives of integral line casting type machines a wiping member movable lengthwise of the knives and located in position to remove from the knives metal adhering thereto and a lug carried by the wiper and engaging a fixed element of the machine to hold said wiping member in spaced relation with respect to the knife edges.

10. In combination with a slug-trimming knife of an integral line casting type machine a wiping member, means urging said member toward the knife edge and means for holding said member in spaced relation with respect to said knife edge.

11. In combination with the slug-trimming knives of integral line casting type machines, a wiping member movable with respect to said knives to remove material from the knife edges and means actuated by a periodically operated element of the machine independent of the first elevator, operatively connected to said member for imparting a wiping movement thereto.

CHARLES A. SPICKLER. 50
